The diagram shows a cross-sectional view of a cylinder assembly. The outer boundary is a hatched rectangle labeled 14. Inside, a central tube is labeled 26. The tube is supported by a U-shaped bracket at the top, which is secured to the outer wall by three bolts labeled 14C. The bottom of the tube is supported by a U-shaped bracket, which is secured to the outer wall by three bolts labeled 14B. The bottom of the tube is also labeled 14A. The entire assembly is labeled 8.

UNITED STATES PATENT OFFICE.

ALBERT TOWE, OF CHARLOTTE, MICHIGAN.

MACHINE FOR BENDING SCYTHE-SNATHS.

No. 841,857.

Specification of Letters Patent.

Patented Jan. 15, 1907.

Application filed May 27, 1904. Serial No. 210,136.

To all whom it may concern:

Be it known that I, ALBERT TOWE, a citizen of the United States, residing at Charlotte, in the county of Eaton and State of Michigan, have invented a new and useful Machine for Bending Scythe-Snaths, of which the following is a specification.

This invention relates to machines for bending scythe-snaths.

10 The object of the invention is in a rapid and practical manner without danger of splintering the snath-blank and in one operation to impart to the blank all the bends necessary to produce a finished snath.

15 With the above and other objects in view, as will appear as the nature of the invention is better understood, the same consists in the novel construction and combination of parts of a machine for bending scythe-snaths, 20 as will be hereinafter fully described and claimed.

In the accompanying drawings, forming a part of this specification, and in which like characters of reference indicate corresponding parts, Figure 1 is a view in vertical longitudinal section through the machine. Fig. 2 is a view in perspective of the former, exhibiting the upper side thereof. Fig. 3 is a plan view of the former, showing the under side thereof. Fig. 4 is a view in rear elevation of one of the plungers. Fig. 5 is a transverse sectional view through the former and plunger. Fig. 6 is a detail view of one of the abutments. Fig. 7 is a detail view of one of the shields 30 acting with the plunger. Fig. 8 is a sectional detail view of a part of the plunger. Fig. 9 is a horizontal sectional view taken on the line 9 9, Fig. 1, and looking in the direction of the arrow thereon. Fig. 10 is a similar view 35 taken on the line 10 10, Fig. 1. Fig. 11 is a similar view taken on the line 11 11, Fig. 1. Fig. 12 is a similar view taken on the line 12 12, Fig. 1. Fig. 13 is a detail view in elevation of the plungers, showing more particularly the configuration of the under faces 40 thereof.

The machine of the present invention embodies in its construction a bed 1, a former 2, a plurality of flexible or yieldable plungers 3, 4, and 5, guards 6 and 7, coacting with the snath-blank 8 through the former, and an adjustable angular abutment 8, which by coaction with the guard 7 imparts the desired end

55 pressure to the blanks as they are forced through the former.

The frame of the machine comprises in this instance a base 9, a pair of standards 10, and a cross-piece 11, connecting the upper ends of the standards and bracing them against movement in the operation of the machine. The former 2 is suitably secured to the standards 10 against any tendency to movement and comprises a metallic body having a channel 12, that extends longitudinally and vertically therethrough and which, in effect, constitutes the former, the upper end of the channel being straight to receive the blank in its initial form, as shown in Fig. 2, and thence gradually merges into curves that taper laterally from the plane of the opening and that terminate at the bottom of the body in an opening 13 of the exact shape of the snath when viewed in plan, as shown in Fig. 3, or, in other words, the opening 13 imparts all of 75 the belly or horizontal bends to the snath-blank.

In order to reduce friction between the snath-blank and the inner walls of the channel, the latter are provided with ribs 14, 80 which may be of any number and spaced at any desired distance apart. The former, as shown in Figs. 2 and 3, is composed of two side plates 2^a and 2^b and two end plates 14^a and 14^b, the latter being held combined with 85 the former by bolts 14^c, which project from the ends of the side plates, and nuts 14^d, seated on the bolts.

The bed supports a hollow form 15, which receives the blank from the mouth 13 of the former. The upper surface of the bottom of the form has all of the vertical snath bends, and, in conjunction with the plungers, the under faces of which have all of the vertical bends of the blank, but in reverse order to 95 those of the form, as shown in Fig. 13, imparts to the blank all the vertical bends, the form being designed to retain the bent blank until it is dry. The bed 1 rests upon a plurality of coiled springs 16, that are interposed 100 between it and the base 9 and are adapted to yield to excessive pressure, and thus remove any danger of breaking the form in the operation of the machine.

At one end of the former is arranged the 105 angular abutment 8, the inner face of which is inclined outward from its upper end toward the bed, the object of which is to im-

part end pressure to the blanks as they are forced through the form, and thus operate to crowd the grain of the blank from its ends inward toward its center, and thereby ob-

- 5 viate danger of stretching or breaking the fibers at the outer side or bulge of the belly of the blank. The abutment is in this instance shown as interposed between the end plate 14 and the ends of the side plates; but, 10 as will be obvious, its position may be transposed without departing from the spirit of the invention. The abutment is made adjustable vertically, so as to increase or diminish the end pressure, as may be necessary, and 15 this is effected by providing the abutment with a plurality of longitudinal slots 16^a, through which project the bolts 14^a.

The plungers 3, 4, and 5 are each composed of a series of sections 17, articulated to 20 each other and adapted to yield laterally in a horizontal plane in order to pass through the channel 12, as will be readily understood by reference to Figs. 10, 11, and 12.

Each of the standards 10 is provided on its 25 inner face with a vertical guideway 18, Fig. 9, the two guideways being adapted to be engaged by guides 18^a, carried by the upper sections of plunger-actuating bars 19, each of which is composed of two sections connected 30 by a ball-and-socket joint 20, each upper section 21 having a rack-plate 22 secured to it and each lower section 23 being suitably connected with the plunger-sections. By the 35 employment of the ball-and-socket joints the lower sections will be permitted to have inward, outward, and lateral movements without interfering with the upper sections, thus to cause the plungers to accommodate themselves to the different positions to which 40 they will be moved in use.

In order to hold the sections 17 of the terminal plungers against dropping, stay-rods 24 are provided, one end of each of which is mounted between a pair of ears 25 on the actuating-bar section 23 and the other end between a pair of ears 26 on one of the sections 45 17. The terminals of the stay-rods are held pivotally secured between the pairs of ears 25 and 26 by pins 27, each of which has reduced extremities to work in the ears and an intermediate ball or rounded portion upon which the terminals of the stay-rod may rock, thus to allow the sections 17 to yield to the contour of the channel of the former, the 50 construction of the pins 27 being shown in detail in Fig. 8. The center plunger is the same in construction as the two end plungers, except that it is about double their length and its sections are supported by two stay- 55 rods 28.

In addition to securing the function defined the stay-rods 24 and 28, in conjunction with the lower sections 23 of the plunger-actuating bars 19, operate to retain the plunger-

sections 17 in position to cause their under 65 faces always to preserve the curves of the vertical bends of the snath.

The plunger-actuating bar 29 of the center section engages a guideway 29^a and is provided at its upper portion with a rack 30, and this rack, as well as the racks 22 of the plunger-actuating bars 19 and 21, are engaged by gear-wheels 31, that are driven from any suitable source of power. (Not necessary to be shown.)

In order to guide the snath-blank through 75 the former and to prevent any interference between its ends and the ends of the channel of the former, the outer terminal section 32 of each of the plungers 3 and 5 is provided with the guards 6 and 7, above referred to, 80 which consist of depending flanges that bear against the terminals of the blank. Thus as the plungers are forced into the channel of the former these guards will bear, respectively, at one end against an end wall 85 of the channel and at the other end against the abutment 8, and the latter by coaction with the guard 7 will exert the desired end pressure, and the two guards will insure ready passage of the blank through the channel 90 without resistance.

In order to prevent the blank from splintering, there is a flexible shield or jacket combined with each of the plunger-sections, that are adapted to yield to the movement 95 of the sections, and by being interposed between the snath-blanks and the walls of the channel the blanks are positively shielded against injury by contact with the walls, and any tendency of the fibers to splinter at the inner or outer curves of the belly bend of the blank is positively obviated. Ordinarily one shield will be sufficient to be combined with each plunger; but, if preferred, there may be one on each side, so that both sides 105 of the blank will be protected by a flexible guard.

When the blank is being bent, there is a tendency for the small end to spring away from the plunger, and if this be permitted 110 the benefits secured from the end pressure will be lost and the fibers will be permitted to stretch, and thus allow the blank to splinter at the sharper bends. To obviate this, there is combined with the plunger 3 a dog 34, that 115 is approximately triangular in shape and is secured to a flat spring 35, attached to the plunger, the dog being provided with a shoulder 35^a, upon which the end of the snath is designed to rest, as shown in Fig. 5. 120 As the plungers descend and the bends are imparted to the blank the lower inner face of the dog contacts with the form 15, and as the said face is inclined the downward movements of the plunger will operate to force the dog laterally, and by the time the snath-blank has come directly over the form the dog will have been pushed away from the 125

snath to permit the latter to enter the form. In order to allow the requisite lateral movement of the dog for the purpose stated, the inner face of one wall of the former is provided with a recess or chamber 36, as shown in Fig. 5.

The operation of the machine is as follows: The plungers being raised above the upper face of the former, a blank is placed over the mouth of the former and against the shields or jackets 23 and the machine is started. As soon as the plungers pass the straight mouth of the channel the shields all contact with the curved walls thereof and in yielding thereto cause the snath gradually to receive all of the belly bends, and by the time the blank is ready to be forced into the form 15 all of such bends will have been completely formed. As the blank passes from the former to the form the continued downward movement of the plungers will impart to it all of the vertical bends, thereby completing the operation. As soon as this has been effected the plungers are raised, another form is placed beneath the former, and the operation is repeated, as before.

It will be seen from the foregoing description that although the machine of this invention is exceedingly simple of construction it 30 will be found of the highest efficiency and durability in use and will result in the rapid production of a finished and even product without the least possible danger of spoilage by splintering, cracking, or the like.

35 I claim—

1. In a machine for bending scythe-snaths, the combination with a former having a channel departing laterally from the plane of its opening, of a plunger embodying a horizontal series of sections articulated to each other to yield laterally in a horizontal plane by contact with the walls of the channel, and reciprocatory actuating-bars combined with the plunger.

45 2. In a machine for bending scythe-snaths, the combination with a former having a channel departing laterally from the plane of its opening, of a plunger embodying a horizontal series of sections articulated to each other to yield laterally in a horizontal plane by contact with the walls of the channel, reciprocatory actuating-bars, and means for yieldably connecting the sections and the actuating-bars.

55 3. In a machine for bending scythe-snaths, the combination with a former having a channel departing laterally from the plane of its opening, of a plunger embodying a horizontal series of sections articulated to each other to yield laterally in a horizontal plane by contact with the walls of the channel, and flexible shields combined with the sections and projecting in advance thereof in the plane of travel.

4. In a machine for bending scythe-snaths, 65 a former having a channel departing laterally from the plane of its opening to impart all of the horizontal bends to a snath-blank, a form adapted to impart all of the vertical bends to the blank, and a plunger embodying a horizontal series of sections articulated to each other to yield laterally in a horizontal plane and coacting with the form to produce the finished blank. 70

5. In a machine for bending scythe-snaths, 75 a former, a plunger coacting therewith and provided with a resilient hook to hold a snath-blank in operative relation to the plunger, and a blank-receiving form adapted to flex the hook to release the blank. 80

6. In a machine for bending scythe-snaths, a former having a channel departing laterally from the plane of its opening, a plurality of articulated plungers coacting with the former, means carried by one of the plungers 85 to hold the snath-blank in cooperative relation thereto, and means to release the blank-holding device.

7. In a machine for bending scythe-snaths, 90 a former comprising side and end plates, the side plates having their opposed faces, provided with spaced ribs and contoured to impart all the horizontal bends to a snath-blank, and an adjustable abutment combined with one end of the former. 95

8. In a machine for bending scythe-snaths, a former having a channel departing laterally from the plane of its opening and provided with an angular abutment, and a plunger embodying a horizontal series of sections 100 articulated to each other to yield laterally in a horizontal plane, and guards carried by the outer ends of the terminal sections.

9. A machine for bending scythe-snaths 105 embodying in its construction, a former having a channel departing laterally from the plane of its opening, a form arranged beneath the channel, and a plunger embodying a horizontal series of sections articulated to each other to yield laterally in a horizontal plane by contact with the walls of the channel and coacting with the form to produce a finished snath, and means for imparting end pressure to the blank. 110 115

10. A machine for bending scythe-snaths comprising a former having a channel departing laterally from the plane of its opening, a plunger embodying a horizontal series of sections articulated to each other to yield laterally in a horizontal plane by contact with the walls of the channel, and a yieldable shield or jacket combined with each of the sections and extending beyond the faces thereof that engage the blank to contact 125 with another face of the blank.

11. A machine for bending scythe-snaths comprising a former having a channel de-

parting laterally from the plane of its opening, a plunger embodying a horizontal series of sections articulated to each other to yield laterally in a horizontal plane by contact with the walls of the channel, a yieldable shield carried by each of the sections, and guards carried by the outer ends of the terminal sections.

In testimony that I claim the foregoing as my own I have hereto affixed my signature in the presence of two witnesses.

ALBERT TOWE.
